DESIGN FOR A HANDLE FOR STOVES OR THE LIKE

Elmer D. Pellegrin, Woodstock, Ill., assignor to
Geo. D. Roper Corporation, Rockford, Ill., a corporation of Illinois

Application January 29, 1940, Serial No. 89,850

Term of patent 7 years

To all whom it may concern:

Be it known that I, Elmer D. Pellegrin, a citizen of the United States, residing at Woodstock, in the county of McHenry and State of Illinois, have invented a new, original, and ornamental Design for a Handle for Stoves or the like, of which the following is a specification, reference being had to the accompanying drawing, forming part thereof.

In the drawing:

Fig. 1 is a perspective view of a handle for stoves or the like showing my new design;

Fig. 2 is a top plan view thereof;
Fig. 3 is a front elevational view thereof;
Fig. 4 is an end elevation thereof, and
Fig. 5 is a cross-sectional view thereof on the line 5—5 of Fig. 3.

I claim:

The ornamental design for a handle for stoves or the like, substantially as shown.

ELMER D. PELLEGRIN.
